(57) **CLAIM**

The ornamental design for a storage container, as shown and described.

DESCRIPTION

FIG. 1 is a front elevational view of a storage container showing my design, the back elevational view being a mirror image;

FIG. 2 is a right side elevational view thereof, the left side elevational view being a mirror image thereof; and,

FIG. 3 is a top plan view thereof, shown at a slightly larger scale.

1 Claim, 3 Drawing Sheets

FIG. 1

FIG. 2

FIG. 3
